FEEDING MECHANISM FOR WRAPPING MACHINES

Clarence J. Malhiot, Oak Park, Ill., assignor to
 F. B. Redington Co., Chicago, Ill., a corporation
 of Illinois

Application November 29, 1940, Serial No. 367,813

21 Claims. (Cl. 93—1)

This invention relates to feeding mechanism for wrapping machines in general, and more particularly for wrapping machines which wrap a Cellophane wrapper about a cigarette package. More specifically, the invention relates to feeding mechanism for a wrapping machine of the type disclosed in applicant's co-pending application filed concurrently herewith, Serial No. 367,812, and assigned to the present assignee.

An important object of the present invention is the provision of new and improved means for continuously feeding wrapping material and tape material to proper position with respect to a continuously moving package about which the wrapping material and tape is to be wrapped.

Another important object of the invention consists in feeding wrapping material continuously and applying tape material to the wrapping material and feeding the taped wrapper to a package-moving conveyor which moves a package through the taped wrapping material.

A further object of the invention is the provision of new and improved feeding means for feeding wrapping material and tape material along a predetermined path and then into convergent paths and into contacting engagement, there being a glue or solvent applied to the tape material prior to the time it comes into physical contact with the wrapping material, whereby the wrapping material with the tape applied thereto is fed in the form of a sheet to a predetermined position to be engaged by an on-coming continuously moving package.

Still another object of the invention is the provision of new and improved feeding means which feeds wrapping material at a predetermined speed prior to the cutting thereof and then advancing the speed of the cut wrapper, whereby the sheets of wrapping material will be spaced apart a predetermined distance upon arriving at a predetermined position, there being tape feeding means operating at a predetermined rate of speed so as to feed tape material along the entire surfaces of the sheets and between the sheets to connect the sheets, whereby a tab will be provided on each cut wrapper of a length equal to the distance between sheets after the tape is cut along an edge coincident with a side or edge of the wrapping material.

A more specific object of the invention resides in the provision of feeding and cutting means for continuously feeding wrapping and tape material, the wrapper material being fed at different speeds to effect spacing of sheets, when severed, and the tape being fed at a predetermined speed

and applied to the severed sheets and connecting the sheets, whereby an opening tab of a length equal to the distance of the space between the severed sheets will be provided as the tape material is cut along an edge coextensive with an edge of the wrapping material.

Other specific objects of the invention consist in the provision of new and improved feeding means which has means for feeding a web of wrapping material to a predetermined position, which is provided with continuously operating cutting means for cutting the wrapper when it arrives at a predetermined position, which is provided with means for feeding opening tape to a predetermined position and applying the tape to the continuously moving wrapper in a predetermined manner, which is provided with improved means for applying a solvent or adhesive to the tape to cause it to be stuck properly to the wrapping material, which is provided with new and improved cutting means for cutting the tape at a predetermined position with respect to an end or edge of the wrapping material, which is provided with means for forming the taped wrapper about the package as the package engages the material and is pushed through the material, and which is provided with new and novel means for operating the various parts synchronously and in proper timed relationship.

Still another object of the invention resides in the location and arrangement of the various parts and the particular construction of the parts to provide for the greatest efficiency of the feeding means.

Numerous other objects and advantages will be apparent throughout the progress of the following specification.

The accompanying drawings illustrate a selected embodiment of the invention, and the views therein are as follows:

Fig. 1 is a detail elevational view of the feeding mechanism as applied to a wrapping machine;

Fig. 2 is a detail elevational view at right angles to Fig. 1 and looking from the left toward the right;

Fig. 3 is a detail vertical sectional view on the line 3—3 of Fig. 2;

Fig. 4 is a detail transverse sectional view on the line 4—4 of Fig. 1;

Fig. 5 is a detail transverse sectional view on the line 5—5 of Fig. 1;

Fig. 6 is a detail longitudinal sectional view on the line 6—6 of Fig. 2;

Fig. 7 is a diagrammatic or schematic view

showing the manner in which the tape is applied to severed successive wrappers; and

Fig. 8 is a detail perspective view of a package after the same has been moved through the feeding means.

The specific feeding mechanism herein shown for the purpose of illustrating the invention is adapted to be applied to the wrapping machine disclosed and claimed in applicant's co-pending application, Serial No. 367,812, filed concurrently herewith and assigned to the present assignee.

The wrapping machine comprises a supporting frame 1 which includes longitudinal rails or side bars 2, spaced cross bars or posts 3 rigidly connecting the side bars or rails 2, and supporting legs, not shown. A conveyor 5 is operatively supported to appropriate parts of the frame 1 and conveys a package to be wrapped to and partly through the wrapping mechanism. Endless chains 8 are trained over sprockets mounted on suitable shafts on the frame, and these chains are operatively connected together by spaced transverse bars 13 which are adapted to act as carriers or pushers for the packages 14 to be wrapped. The transverse bars 13 are arranged a predetermined distance above the conveyor bed 15, and are adapted to engage a package on a longitudinal side thereof between its lower and upper surfaces and convey packages successively along a predetermined path to the wrapping mechanism. A magazine (not shown) is arranged adjacent one end of the conveyor 5 and carries a supply of packages 14 to be conveyed to wrapping position. The magazine has an open bottom to permit the lowermost package of a stack to be engaged by a cross bar 13 and fed toward wrapping position during operation of the conveyor. The cross bars 13 on the conveyor 5 move successive packages through a sheet of wrapping material which is fed downwardly by the wrapper feeding means, indicated generally by the numeral 18. The conveyor and means for operating the conveyor are disclosed and claimed in applicant's aforesaid co-pending application, and co-operate with the feeding mechanism 18 to cause a wrapper to be applied about the package. The machine proper is disclosed and claimed in the co-pending application and forms no part of the present application, except insofar as is necessary for a proper understanding of the present invention covering the feeding means. The present application is restricted to the specific feeding mechanism and such part or parts of the machine as effect the operation of the present feeding mechanism.

The feeding means 18 comprises mechanism for feeding wrapping material in a continuous web from a roll 19 to position to be engaged by a continuously moving package 14. The web of material 19, from which the wrappers 17 are cut, passes over a roller 20 which is mounted on a stud 21 carried by a part 22 fixed to the supporting frame 1, and then between pairs of spaced fingers or guides 23 and 24 to guide the web of material in its downward movement to package wrapping position. The fingers 23 each comprise a rigid member having a hook-shaped end 25 removably mounted on a post 26 extending from a part of the supporting frame structure 22. The hook-shaped end 25 of each member 23 slips over the post 26 and conforms substantially to the shape thereof so as to be rigidly supported, the post 26 and the end 25 being provided with interengaging or limiting means to prevent longitudinal displacement. The spaced

guides 24 are arranged on the opposite side of the web material and co-operate with the guides 23 to guide the wrapping material from the reel 27, which is revolvably supported on a part of the frame superstructure 22.

Feed rollers 28 and 29 feed the material downwardly to a predetermined position where it is cut by the cutters 30 and 31. The feed roller 28 is mounted on a transverse shaft 32 which carries a gear 33 meshing with a gear 34 on a stud shaft 35. The roller 29 is mounted on a shaft 36 which is carried by brackets 37 suspended from the stud 21. The roller 29 is urged toward the driving roller 28 and in contacting relationship therewith by means of a spring 38 arranged between an arm 37 and a bracket 39 rigidly mounted on the stud 21, Figs. 1 and 3. A set screw 40 extends through each bracket arm 39 for the purpose of adjusting the spring tension with respect to the arm 37, whereby the roller 29 may have greater or less pressure against the roller 28, depending upon the adjustment of the spring 38 by the set screw 40, Figs. 2 and 3. The feed rollers 28 and 29 therefore feed the web of material from the roll to the cutters 30 and 31. The cutter 30 is mounted on a shaft 41 which carries a gear 42 meshing with the gear 34 and is driven thereby. The cutter element 30 includes a blade 43 which is adapted to have cutting relationship with the blade 44 of the cutter 31. The cutter 31 is stationary and is mounted in a block 45, Fig. 3, rigidly fixed to a part of the supporting superstructure 22. Therefore, as the rotary cutter 30 operates, the blade 43 will come into cutting relationship with the stationary blade 44 to sever the web into successively cut sheets of wrapping material 17.

Tape 46 is fed from a roll 47, Fig. 1, to position to be secured to the successively cut wrappers, the tape, after leaving its supporting reel, passing over a heating element 48 to iron the tape to take out any kinks or wrinkles to render it flat and smooth. After the tape leaves the ironer 48, it passes over a roller 49, suitably mounted in a part secured to the frame, and then about a roller 50 which is mounted on a stud shaft 51. From the roller 50 the tape passes between rollers 52 and 53, after which it comes into contacting relationship with the severed sheets of wrapping material 17, as indicated at 54, Fig. 3.

The present machine is designed to employ Cellophane as the wrapping material and, therefore, the specific adhesive material used herein is solvent. However, if waxine paper or other material is used as the wrapper, then the adhesive material will be glue or other material to cause the tape to adhere to the wrapper.

The roller 52 is the solvent applying roller which receives a proper amount of solvent by means of a wick 55 having one end in contacting relationship with the roller 52 and its other end immersed in the solvent 56 in the container 57. The solvent container 57 has one of its ends supported on a stationary stud 58 and may be locked thereto by means of a thumb nut 59. One end of the container is adapted to rest against and be supported by a bracket 60 fixed to a part of the frame structure 22. The container 57 also carries a pair of lugs 61 which support the shaft 62 upon which the solvent roller 52 is mounted. The tape 46, as it passes over the roller 53, has solvent applied thereto so that the tape may be stuck to the wrapper 17 as it passes between the roller 53 and a presser

roller 63. The presser roller 63 is mounted on a shaft 64 carried by arms 65 suspended from studs 66. A spring 67, engaging the bracket arms 65 and arms 68 rigid with the studs 66, presses the roller 63 toward the roller 53. Therefore, the tape with the solvent applied thereto is forced against and stuck to successively cut wrappers 17. Set screws 69 in the arm of the brackets 63 are adapted to adjust the tension of the springs 67 to create more or less pressure of the roller 63 against the roller 53. The roller 53 is adapted to be driven by a gear 70 on the stud 71, Fig. 3, the gear 70 meshing with a gear 72 carried by the shaft 73 upon which the roller 53 is mounted. The gear 70 is driven by a driven gear 74 mounted on the shaft 75. The shaft 75 also carries rotary cutting mechanism 76 which co-operates with stationary cutting mechanism 77 to cut the tape at the upper marginal edge of the wrappers 17, as indicated at 78, Fig. 7, whereby there will be provided a projecting part of the tape to provide an opening tab 79.

The cutter 76 carries a cutting blade 80 which is adapted to co-operate with a stationary cutter blade 81 mounted in the block 77. The cutters 80 and 81 are synchronized and operate in proper timed relationship with the feeding mechanism so that when the blades 80 and 81 come into proper cutting relationship, the tape will be cut from the wrapper at the upper marginal edge thereof, leaving the projecting tab 79. The projecting tab 79, therefore, is substantially the same length as the distance between the spaced pre-cut wrappers 17.

The tape 46 is fed at a rate faster than the wrapping material is fed by the rollers 28 and 29, and inasmuch as the rollers 53 and 63 are also feed rollers, feeding the tape at the proper rate of speed, a cut wrapper 17 will be fed faster than the web material, therefore providing spaces 82 between severed sheets 17, the spaces increasing progressively until the tape is applied. The tape is later severed from the spaced sheets by the cutting knives 80 and 81, as shown diagrammatically in Fig. 8.

After the cutting mechanism 76 and 77 has caused the tape to be severed at the point indicated at 78, Fig. 7, the wrapper, with the tape applied thereto, and its extending tab, will be engaged by oppositely disposed feed rollers 83 and 84. The roller 83 may be provided with a circumferential groove 83^a near one end thereof to prevent roller contact with the tape in cases where the tab is at the top instead of at the bottom, as shown, so that the tape will not be further fed independently, but will be fed only by its physical adhesion with the wrapper, Fig. 5. The tab 79, therefore, is free to be drawn through the roller as the package engages the wrapper during the first partial wrapping operation.

The feed roller 83 is mounted on a transverse shaft 85 and carries a gear 86 which meshes with an idler gear 87 mounted on a shaft 88. The gear 87 is driven by the gear 74 on the shaft 75. Each successive severed sheet, with the tape applied thereto and the tab extending therefrom, is thus fed to proper position with respect to the conveyor 5 so that a cross bar or strap 13 on the conveyor 5 will move the package through the sheet in the manner described in the aforesaid application, and as indicated at 89, Fig. 8, with the upper and lower parts 90 and 91 extending rearwardly from the upper and lower surfaces, respectively, of the package 14.

As the sheet 17 is fed between rollers 83 and 84

to position, solvent applying means 92 applies a predetermined amount of solvent across the inside of the lower edge 81, as indicated at 93, Fig. 8.

The roller 84 is adapted to be spring urged against the roller 83 by means of a spring 94 arranged between the hanger arms 95 and a rigid arm 96 rigidly secured to a part of the stationary knife cutting means 77, whereby tension of the roller 84 against the roller 83 may be increased or decreased as desired, by operating the set screw 97, Fig. 3.

The solvent applying means 92 comprises the solvent applicating member 98 co-operating with a backing member 99, as clearly shown and described in the aforesaid co-pending application. The applicators 98 and 99 are mounted on shafts 100 and 101, respectively, being driven by an idler gear 102 mounted on a shaft 103. The gear 102 is adapted to mesh with the gear 86 mounted on the aforesaid shaft 85.

As the package 14 is pushed through the wrapper 17 in the manner described in the aforesaid application and as shown in Fig. 6 herein, the wrapper will be bent around the edge 106 of a block 105. The block 105 is positioned so as to cause proper bending of the wrapper with the underside 106 of the block relatively parallel to the top of the package and in close relationship therewith.

To facilitate tearing of the wrapper by the pulling of the tab 79, the wrapper is provided with spaced slits 107, which are formed at the marginal edge of the wrapper, as shown in Fig. 8. These slits are applied to the wrapping material by cutting or slitting means 108 carried by the roller 29. The rotary roller 28 is provided with spaced grooves to receive the spaced slitters carried by the roller 29, whereby a slit 107 will be formed in the marginal edge of the wrapper on each side of the tab 79, as indicated in Fig. 8.

Supporting guides 110 are arranged beneath the cutters 30 and 31 to guide the severed wrapping sheets 17, and these guides comprise spaced front and rear members 111 and 112 which are provided with spaced relatively triangularly shaped ends, positioned as shown in Fig. 5, so as to put a slight bend in the edge of the wrapper 17 to render the wrapper less flexible and permit it to be fed in relatively rigid form so as to maintain the sheet in proper position, allowing the same to be fed more properly. After a sheet has been fed to lowermost position, as shown in Fig. 1, the on-coming package, which is moved by the conveyor 5, will be pushed through the wrapper in the manner shown in Fig. 8, and then carried forwardly by the pusher arms or bars 13, Fig. 1, to further wrapping position.

The feeding mechanism may be driven by a chain 120 which may drive the other driving parts of the wrapping machine, as defined in the aforesaid co-pending application. The chain 120, which is operated by a sprocket on a motor shaft, not shown, passes over an idler sprocket on the shaft 51 and then over a sprocket on the shaft 38. The chain then extends downwardly, Fig. 3, and drives a sprocket fixed on the shaft 75. From this latter shaft, the chain 120 extends longitudinally of the machine to drive other operating parts as disclosed in said aforementioned application.

Operation

The feed means 18 causes the continuous sheet or web of wrapping material to be continuously

fed from the reel 27 by the feed rollers 28 and 29 to a position to be cut by the cutter blades 43 and 44 on the cutting elements 30 and 31, respectively. The opening tape 46 is fed from a roll of tape 47, Fig. 1, to position between the rollers 52 and 53 where solvent is applied to one side of the tape. The tape then passes over the roller 53 until it comes into contacting relationship with a cut web of material which passes between the rollers 53 and 63. The feed rollers 53 and 63 operate faster than the web feed rollers 28 and 29, whereby a space is provided between adjacent sheets, as clearly shown in Fig. 7. However, the tape material operates at a faster speed than the feeding movement of the wrapping material until the wrapper engages the feed rollers 63 and 53, at which time the tape and wrapper 17 feed at the same speed. The difference in speed between the feed of the continuous wrapper and the subsequent feed of the sheets 17, as well as the feed of the tape 46, will cause the tape to be applied to the spaced sheets 17, as clearly shown in Fig. 7, whereby the spaced sheets will be connected by the tape. As the cut sheets 17 with the tape thereon have been fed to proper position, the tape is caused to be cut along a marginal edge of the wrapper so as to provide an opening tab 79 substantially the same length as the distance between sheets. After the tape has been severed, the sheet with the tape applied thereto, and the tab extending therefrom, will be fed to position where it will be engaged by an on-coming package which is forced through the wrapper in the manner shown in Fig. 8, and then carried on to further folding operations by means of the continuously operating conveyor 5.

The invention provides positively operating, relatively simple feed means comprising a plurality of parts and mechanisms all properly correlated and synchronized so that the proper feeding and cutting steps occur at precisely the proper time. Moreover, the feed mechanism is driven by the same driving means which operates the other operating parts of the wrapping machine, whereby the feed means operates in proper timed relationship with respect to other operating parts of the machine. However, as soon as the wrapper is arranged in position to be engaged by an on-coming package, the overhanging lower end of the wrapper is provided with solvent so that the wrapper may be secured to the package. The invention also provides means for effecting continuous feed operation of both the web of material as well as the tape material, so as to cause the web to be cut at the proper time interval and then spaced from the next succeeding sheet a predetermined distance. The cut sheets then have applied thereto the continuously moving tape material, so as to interconnect all the sheets. The tape is then later disconnected by severing it along a marginal edge of a sheet to provide a tab of the proper length. The feed mechanism is strong and durable in construction, efficient in operation, and is adapted to be readily and economically manufactured.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. A wrapping machine comprising means to feed a web of wrapping material continuously to a predetermined position, means for cutting the web of material into sheets, means to apply a continuous strip of tape to a plurality of said cut sheets, and means to cut the tape along a marginal line of each sheet.

2. A wrapping machine comprising means to feed a web of wrapping material continuously to a predetermined position, means for cutting the web of material into sheets, means for feeding tape to a predetermined position, means to apply a substance to a side of the tape, means to feed a continuous strip of the tape to the wrapper sheets to stick the continuous strip of tape to a plurality of the severed sheets, and means to cut the tape along a predetermined edge of each sheet.

3. Feeding mechanism for wrapping machines comprising means for feeding a continuous web of wrapping material continuously from a roll of wrapping material, means to cut the web of material into sheets, means to space the sheets apart, and means to apply a continuous strip of tape material to a plurality of said spaced sheets to connect said sheets.

4. Feeding mechanism for wrapping machines comprising means for feeding a continuous web of wrapping material continuously from a roll of wrapping material, means to cut the web of material into sheets, means to space the sheets apart, means to apply a continuous strip of tape material to a plurality of said spaced sheets to connect said plurality of sheets, and means to cut the tape along a marginal edge of said sheets to provide a tab on each sheet.

5. Feeding mechanism for wrapping machines comprising means for feeding a continuous web of wrapping material continuously from a roll of wrapping material, means to cut the web of material into sheets, means to space the sheets apart, means to apply a continuous strip of tape material to a plurality of said spaced sheets to connect said sheets, and means to sever the tape between spaced sheets to provide a tab extending from an end of each sheet.

6. Wrapping machine feed mechanism comprising means for feeding a web of wrapping material continuously at a predetermined speed from a roll of material, means for severing said web into sheets, means for feeding the sheets at a faster speed than the feeding speed of the web to space the sheets apart, means to feed tape continuously to said sheets and stick the tape to said sheets and thereby connect the sheets together, and means for severing the tape between sheets.

7. Wrapping machine feed mechanism comprising means for feeding a web of wrapping material continuously at a predetermined speed from a roll of material, means for severing said web into sheets, means for feeding the sheets at a faster speed than the feeding speed of the web to space the sheets apart, means to feed tape continuously to said sheets and stick the tape to said sheets and thereby connect the sheets together, and means for severing the tape along a marginal edge of each sheet to provide a wrapper having an opening tape with an extending opening tab.

8. Wrapping machine feed mechanism comprising means for feeding a web of wrapping material continuously at a predetermined speed from a roll of material, means for severing said web into sheets, means for feeding the sheets at a

faster speed than the feeding speed of the web to space the sheets apart, means to feed tape continuously to said sheets and stick the tape to said sheets and thereby connect the sheets together, means for severing the tape along a marginal edge of each sheet to provide a wrapper having an opening tape with an extending opening tab, and means to feed said last named wrapper to a predetermined position.

9. Wrapping machine feed mechanism comprising means for feeding a web of wrapping material continuously at a predetermined speed from a roll of material, means for severing said web into sheets, means for feeding the sheets at a faster speed than the feeding speed of the web to space the sheets apart, means to feed tape continuously to said sheets and stick the tape to said sheets and thereby connect the sheets together, means for severing the tape along a marginal edge of each sheet to provide a wrapper having an opening tape with an extending opening tab, rotary feed means for receiving said last named wrapper with opening tape and tab attached and feeding it to a predetermined package receiving position, and means to apply a sticking substance along an edge of the wrapper when at said predetermined position.

10. Wrapping machine feed mechanism comprising means for feeding a web of wrapping material continuously at a predetermined speed from a roll of material, means for severing said web into sheets, means for feeding the sheets at a faster speed than the feeding speed of the web to space the sheets apart, means to feed tape continuously to said sheets and stick the tape to said sheets and thereby connect the sheets together, means for severing the tape along a marginal edge of each sheet to provide a wrapper having an opening tape with an extending opening tab, rotary feed means for receiving said last named wrapper with opening tape and tab attached and feeding it to a predetermined package receiving position, means to apply a sticking substance along an edge of the wrapper when at said predetermined position, and means to push a package through said wrapper when the wrapper is at said last named position.

11. Wrapping machine feed mechanism comprising means for feeding a web of wrapping material continuously at a predetermined speed from a roll of material, means for severing said web into sheets, means for feeding the sheets at a faster speed than the feeding speed of the web to space the sheets apart, tape feed means to feed tape continuously to said sheets and stick the sheets together with the tape, means for feeding the tape at the same speed as the cut sheets, and means to cut the tape between sheets at a marginal edge to provide each sheet with an extending tab substantially as long as the space between sheets.

12. Wrapping machine feed mechanism comprising means for feeding a web of wrapping material continuously at a predetermined speed from a roll of material, means for forming spaced slits in the web at predetermined spaced intervals, means for severing said web into sheets, means for feeding the sheets at a faster speed than the feeding speed of the web to space the sheets apart, tape feed means to feed tape continuously to said sheets and stick the sheets together with the tape, means for feeding the tape at the same speed as the cut sheets, and means to cut the tape between sheets at a marginal edge to provide each

sheet with an extending tab substantially as long as the space between sheets.

13. Wrapping machine feed mechanism comprising an upright supporting framework, feed means including contacting rollers for feeding a web of wrapping material continuously, slitter means carried by said feed means to form short longitudinal spaced slits near a marginal side edge of the web at predetermined intervals, means for severing sheets from the web at one end of the slits, means for spacing said sheets when severed, means for applying a continuous strip of tape to a plurality of successive spaced sheets between said slits, and means for cutting the tape between spaced sheets.

14. Wrapping machine feed mechanism comprising means to feed a web of wrapping material, means for forming spaced slits in the web at predetermined spaced intervals, means for cutting the web at the ends of the slits to form sheets, means for spacing the sheets, means for applying a continuous strip of tape to a plurality of the spaced sheets between the slits, and means for cutting the tape between sheets.

15. Wrapping machine feed mechanism comprising tape feed means, means for feeding wrapping material in a downward direction, a feed roller for assisting in such feeding movement, a second feed roller spring pressed against the first named feed roller, said tape feed means providing for feeding the tape in a downward direction and then in an upward direction, and means for applying an adhesive substance to the tape, said tape passing over the first feed roller to be fed in a downward direction between both said rollers and into adhering contact with the wrapping material.

16. An apparatus for applying tearing tabs to package wrappers before applying the wrappers to packages comprising means for feeding a plurality of sheets of wrapping material, means in said feed means for spacing successive sheets a predetermined distance apart while continuously feeding the sheets forward, means for feeding a continuous strip of tape to a plurality of said sheets to stick the tape to said sheets and thereby connect the sheets together while still in sheet form and prior to application of the sheets to articles to be wrapped therein, and means for severing the tape between said connected sheets before applying the sheets to said articles.

17. An apparatus for applying tearing tabs to package wrappers before applying the wrappers to packages comprising means for continuously feeding a plurality of sheets of wrapping material, means in said feed means for spacing sheets a predetermined distance apart while continuously feeding the sheets forward, means for continuously feeding a continuous strip of tape, means for applying said continuous strip of tape to a plurality of said sheets while still in sheet form and prior to application of the sheets to articles to be wrapped therein to stick the tape to said sheets and thereby connect the sheets together, and means for severing the tape between said connected sheets before applying the sheets to said articles.

18. The method of applying opening tapes to package wrappers by extending the tape beyond an edge of the wrappers before the wrappers are applied to packages, which comprises feeding a continuous web of wrapping material continuously from a roll, cutting the web of material into sheets, spacing the sheets apart while continuously feeding the sheets forward, applying a continu-

ous strip of tape material to a plurality of said spaced sheets while still in sheet form and prior to application of the sheets to articles to be wrapped therein thereby to connect said sheets together, and then severing the tape between spaced sheets before applying the sheets to said articles to provide a tab extending from each sheet.

19. A method for wrapping packages which comprises feeding a web of wrapping material continuously at a predetermined speed from a roll of material, severing said web into sheets, feeding the sheets at a faster speed than the feeding speed of the web to space the sheets apart, feeding tape continuously to said sheets and sticking the tape to said sheets to thereby connect the sheets together, and thereafter severing the tape between sheets.

20. A method for applying tearing tabs to package wrappers before applying the wrappers to packages which comprises continuously feeding a plurality of wrapping sheets, spacing said sheets a predetermined distance apart while continuously feeding the sheets forward, continuously feed-

ing a continuous strip of tape to a plurality of said sheets to stick the tape to said sheets and thereby connect the sheets together while still in sheet form and prior to application of the sheets to articles to be wrapped therein, and then severing the tape between said connected sheets before applying the sheets to said articles.

21. The method of making wrappers for wrapping packages and having opening tabs on the wrappers whereby the wrappers on the packages may be opened by pulling the opening tab, which consists in feeding a continuous web of wrapping material continuously, feeding a continuous web of tape material continuously, then cutting the wrapping material to form sheets, then accelerating the movement of the cut sheets to provide spaces between adjacent sheets, then applying the moving tape to the cut moving sheets and between the spaced sheets to connect the spaced sheets together by the tape, and finally severing the tape between the sheets to provide a tab projecting from an edge of the sheet.

CLARENCE J. MALHIOT.
